ATTORNEY

UNITED STATES PATENT OFFICE

RUSSELL J. GRAY, OF MINNEAPOLIS, MINNESOTA

GREASE GUN

Application filed April 20, 1929. Serial No. 356,668.

This invention relates to lubricating equipment and the main object is to provide a simple, efficient, and practical design of manually operative high pressure grease gun, that is particularly adapted for forcibly supplying grease to fittings such as are commonly supplied on motor cars and other machinery. Further and more specific objects will be disclosed in the course of the following specification, reference being had to the accompanying drawings, wherein:

Fig. 1 is an elevation of my improved grease gun, the major portion being shown in diametrical section, and with the piston 15 in the position assumed when the cylinder is empty of grease.

Fig. 2 is a diametrical section of the gun and showing it as partly filled with grease.

Fig. 3 is a sectional elevation similar to Fig. 2, but showing the piston in an advanced position.

Referring to the drawing more particularly and by reference characters, 4 designates a cylinder in which operates a piston 5. The piston 5 is secured to one end of a sleeve 6, the opposite end of which is slidably mounted on a rod 7 that extends through a cap 8, of the cylinder 4, to a handle 9 having a knob portion 10. The cap 8 has a spring depressed pin 11 that normally rests against the bar 7 but when the sleeve 6 is pulled back its tapered end 12 moves the pin up, or out, until it can drop into an annular groove 13 in the sleeve. The piston 5 is normally pressed forward, i. e., away from the cap 8, by a spring 14, and this spring must of course be compressed when the piston is to be pulled back for locking engagement with the pin 11. The pin 11 is provided with a button head 15 by which it may be released to permit the piston to move forward. The forward end of the bar or rod 7 is provided with an integral collar 16, for stopping engagement with the sleeve 6, and has a rigid forwardly extending pin or finger portion 17 that serves as and may be conveniently designated as a plunger. The forward end of the plunger 17 is pointed or tapered, as at 18, so that it will better

sunk axial opening or chamber of a barrel 19, which barrel is detachably secured to the cylinder 4 by a trunco-conical collar 20. The barrel 19 has a check valve 21 at its forward end, and terminates in a connector nipple 22 for convenient connection to the fitting of the bearing or other element to be lubricated.

The operation of the device may be briefly described as follows: To load the grease gun the barrel 19 is unscrewed from the collar 20, or the collar 20 may be unscrewed from the cylinder 4. In either event the cylinder is thus provided with a large opening at its front end, and the front end of the cylinder is then emerged in a supply of grease, and is preferably held in one hand while the other hand of the operator grasps the handle 9 and pulls it away from the cylinder. By so doing the collar 16 engages the sleeve 6, and pulls the piston 5 back until the pin 11 is snapped into locking engagement with the annular groove 13 of the collar. In this manner the cylinder is filled with grease, and the piston is locked so that the spring 14 cannot push it forward until after the barrel 19 has again been attached to the cylinder. At this time the operator grasps the button 15 and by giving it a short pull releases the pin 11 from the sleeve 6, and thus permits the pressure of the spring 14 to act on the piston 5. The spring of the check valve 21 has sufficient tension to hold the valve closed against the action of the spring 14, so that no leakage will occur. When a bearing or other part having the necessary fitting is now to be lubricated the connector 22 is applied to the fitting and the operator then pushes the rod 7 forward until the plunger 17 enters the barrel 19. This action shuts the barrel 19 off from communication with the cylinder, and leaves a charge of grease in the barrel. The operator then gives the knob 10 a blow or substantial push with his hand, which action forces the charge of grease in the barrel 19 through the valve 21 and out through the connector 22 to the fitting, as indicated in Fig. 3. The handle 9 is now pulled back until the barrel 19 is again open to the cylinder 4, upon which the piston 5, under the action of

the barrel 19 from the supply of lubricant in the cylinder 4. The operation is then repeated in the manner previously noted to expel the excessive charges of grease that have been fed to the barrel 19.

It may here be stated that the reason for providing the piston 5 with the sleeve 6, into which the collar 16 and plunger 17 are drawn, as shown in Fig. 2, is that this construction permits the piston 5 to be advanced the full length of the cylinder 4, so that practically all of the grease in the cylinder can be utilized before it is again necessary to refill it. There is, of course, sufficient clearance between the collar 16 and the inner periphery of the sleeve 6 to permit the collar to be drawn into the sleeve, as shown.

It is understood that suitable modifications may be made in the structure as disclosed, provided such modifications come within the spirit and scope of the appended claims.

Having now therefore fully illustrated and described my invention what I claim to be new and desire to protect by Letters Patent is:

1. A grease gun comprising a cylinder, an ejector barrel at one end of the cylinder, a piston in the cylinder, a spring urging the piston toward the ejector barrel, a sleeve having an open end secured to the piston and having its other end closed, a rod slideable in the closed end of the sleeve and through one end of the cylinder, a stop member carried by the rod, for engagement with the closed end of the sleeve, a plunger carried by the inner end of the rod for engagement in the ejector barrel, said plunger being movable into the piston sleeve so as to permit a maximum advance movement of the piston in the cylinder.

2. A grease gun comprising a cylinder, an ejector barrel at one end of the cylinder, a piston in the cylinder, a spring urging the piston toward the ejector barrel, a sleeve carried by the piston, said sleeve having an open end and one closed end, a rod slideable in the sleeve and through one end of the cylinder, a plunger carried by the inner end of the rod for engagement in the ejector barrel, said plunger having freedom for passage into the piston sleeve through the open end thereof so as to permit a maximum advance movement of the piston in the cylinder, and a stop member carried by the rod and movable into the sleeve with the plunger so as to stop against the closed end of the sleeve.

Signed at Minneapolis, in the county of Hennepin, and State of Minnesota, this 18th day of April, 1929.

RUSSELL J. GRAY.
